OUTDOOR LIGHT POST

Donald Deskey, 222 Central Park S., New York, N.Y.
10019, and Alexander Lurkis, 193-12 Nero Ave., Holliswood, Jamaica, N.Y. 11423

Filed July 13, 1965, Ser. No. 86,139

Term of patent 14 years

(Cl. D48—31)

The broken line showing of luminaires and a base in FIGURE 1 is for illustrative purposes only. FIGURES 3, 4, and 5 are shown broken away for convenience of illustration.

We claim:

The ornamental design for an outdoor light post, as shown and described.
